UNITED STATES PATENT OFFICE.

WALTER W. BEELER, OF BALTIMORE, MARYLAND.

BRUSH-HOLDER.

SPECIFICATION forming part of Letters Patent No. 717,656, dated January 6, 1903.

Application filed April 26, 1902. Serial No. 104,815. (No model.)

To all whom it may concern:

Be it known that I, WALTER W. BEELER, of Baltimore city, State of Maryland, have invented a certain new and useful Brush-Holder, 5 of which the following is a specification.

My present invention relates to brush-holders for holding carbon brushes or brushes made of any other material used to collect electric currents from the commutator-cylinder of a dynamo and for delivering such currents to the commutators of motors, and has reference more particularly to improvements whereby as many brush-holders as may be needed can be used, and each brush-holder, 10 if more than two are used, can be easily and readily replaced without interfering with the operation of the commutator, at the same time securing cheapness of manufacture.

The invention is also designed to overcome 20 the destruction of the tension-spring by electric currents by placing the tension-spring beyond the pin of the yoke of the commutator.

In the accompanying drawings, Figure 1 25 shows a side elevation of the brush-holder containing a brush complete as applied to a commutator-cylinder. Fig. 2 shows inside elevation of the brush-holder with one side off, showing the connection of the parts and 30 with the brush out. Fig. 3 shows a back view of the curved portion of the brush-holder, showing the spring, tension screw or pin, thumb-screw, and guide. Fig. 4 shows in perspective the top of the curved end of the 35 brush-holder with the projections *c c* thereon, together with the thumb-screw with the slots *o o* cut therein and the tension screw or pin with guide.

A, Fig. 1, indicates the commutator-cylinder, made up, as usual, of a series of conducting plates or segments insulated from one another, and D indicates the commutator-brush, which is held in a hole provided therefor in the 40 end of the brush-holder C.

B indicates the hole through which the pin of the yoke of the commutator passes and to which the brush-holder is made tight and held in any position desired by an ordinary screw Y, as indicated in Fig. 2.

C is the frame of the brush-holder and is made, preferably, of brass, and it has a hole cut in the end, as indicated by R in Fig. 2,

through which passes and fits snugly the brush D.

H is a bent lever pivoted to the upright of 55 C at S, at one end of which is pivoted at X a piece of brass E, that moves easily backward and forward and presses down on the brush and keeps the brush in contact with the commutator-cylinder A. At the other end of the 60 lever H at K is attached a spiral spring G, said spring being connected with a pin or rod L. Near one end of this pin or rod L is a flat head P, that projects beyond and behind the edges of C, which acts as a guide and keeps 65 the spring in place and line, as indicated in Fig. 4. At the other end of this pin or rod L is screwed the thumb-screw O. Under the bottom of the thumb-screw O are cut the grooves *o o*, which are made to fit upon the 70 projections *c c*, as indicated in Fig. 4, so that when it is screwed down as tight as needed these grooves *o o* and projections *c c* lock and prevent the thumb-screw from working loose.

The regulation of the pressure of the brush 75 D upon the commutator A is controlled by the spring G.

The tightening of the thumb-screw O forces the end of the lever H, with the movable piece E, down upon the brush D and keeps it always in contact with the commutator A. The 80 grooves in the thumb-screw O and the projections in C, as illustrated in Fig. 4, keep the said screw tight and prevent the tension on the brush from increasing or decreasing 85 by the jarring of the machine incident to its operation. The spring being located beyond the place where the brush-holder is attached to the pin on the yoke of the commutator, the 90 electric current passes from the commutator into the brush-holder and is carried away by said pin on the yoke of the commutator without coming in contact with the spring. Thus the tension of the spring is not destroyed or affected by the electric current. 95

What I claim as my invention is—

1. A commutator-brush holder the back portion of which is bent, a rod with guide, a bent lever, a screw for tightening and holding the brush-holder in whatever angle desired to the pin of the yoke of the commutator, a spiral spring, means for adjusting the tension of said spring, a movable piece pivoted to the end of the bent lever, there being 100

a hole cut in the end of the brush-holder in which fits the brush substantially as set forth.

2. A commutator-brush holder consisting of a bent lever, a movable piece pivoted to the end of said lever, a rod with guide, a spiral spring, means for adjusting the tension of said spring, a screw to tighten and hold the brush-holder in any position desired

to the pin on the yoke of the commutator, there being a hole in the end of the brush-holder in which the brush fits substantially as set forth. 10
